Inventor:

Walter T. Abel,
by Parker Cook.
Atty.

UNITED STATES PATENT OFFICE.

WALTER T. ABEL, OF WATERBURY, CONNECTICUT, ASSIGNOR TO THE PATENT BUTTON COMPANY, OF WATERBURY, CONNECTICUT, A CORPORATION OF CONNECTICUT.

TACK BUTTON.

Application filed June 20, 1928. Serial No. 286,891.

My invention relates to new and useful improvements in buttons, and more particularly to a form of button known as a "tack button".

As is well known to those skilled in the art, tack-buttons consist of a button head and a fastening member, in the form of a tack, which latter is driven up through the goods into the button head and bent or mutilated, so that it will be impossible after the tack is once applied for the button head to become detached or lost from the garment.

These buttons are used principally on over-all, working-men's suits or other similar garments, wherein there will be a great strain on the buttons.

The buttons and tacks are applied by using a fastening machine, which mechanically forces the respective tacks into the respective heads in a remarkably rapid manner.

When the tacks are applied, they are so mutilated or bent when in their final position, that it is impossible for the button to ever become disengaged or lost from the garment.

One of the objects of the present invention, therefore, is to provide a tack-button of this type, which consists of a shell in which there is placed a solid steel slug or anvil which in turn is provided with a shank, which shank has an opening so that the tack may be driven through the shell up into the slug or anvil, and the tack there so bent that it will tightly hold the button head with relation to the goods through which the tack has passed.

Still another object of the invention is to produce a tack button, the head of which comprises simply a shell, an anvil or slug, a second small plate, and a cover for the button head. These parts are also so arranged that when the tack is driven through a small opening in the bottom shell, it will force some of the stock of the shell into the opening in the bottom of the recess in the shank of a solid steel slug so that this stock will help support the tack in the opening and add rigidity to the whole assembly.

Still another object of the invention is to provide a tack button which consists of relatively few parts, and so formed that after the tack is applied, the button and connection will be stronger than the form of buttons now in use.

Still another object of the invention is to provide a button relatively cheap to manufacture, easily assembled, and very efficient and strong in service.

With these and numerous other objects in view, the invention consists in certain new and novel arrangements and combination of parts, as will be hereinafter more fully described and pointed out in the claims.

Referring now to the drawings showing a preferred embodiment of the invention,

Fig. 1 is a top plan view of the complete button parts being broken away for the sake of illustration.

Fig. 2 is a vertical section thereof.

Fig. 3 is a vertical section of the anvil in inverted position before the same is swedged or rolled down.

Fig. 4 is a similar view after the swedging.

Fig. 5 is a vertical sectional view of the button back as it appears before assembly and the tack is within the same.

Fig. 6 is a perspective view of the parts, before assembling, and

Fig. 7 is a perspective of the tack.

Referring more particularly to the several parts, there is shown (see Fig. 6) a shell 1, provided with the hub 2, the bottom or base 3, and the outwardly extending rim 4.

Designed to fit within this shell is the slug or anvil 5 which, before being finally shaped will appear as shown in cross section in Fig. 3. This anvil comprises the plate 6 and the hub or shank 7 recessed or hollowed out as at 8, it being understood that in Fig. 3 the said slug is in its inverted position.

Referring now for the moment to Fig. 4, this slug is shown after the walls of the hub or shank 7 have been rolled or swedged inwardly so that now the recess portion 8 is globular or pear-shaped and constricted at its mouth or throat as at 9.

This anvil or slug 5 fits within the shell 1, as may be clearly seen from Fig. 5, together with a small plate 10 that is placed over the top of the anvil or slug so that the upper surface of this plate 10 will lie flush with the edge of the rim 4 of the shell. This plate 10 is slightly larger in diameter than the diameter of the plate 6 of the anvil and makes a solid backing for the cover plate. After these parts are assembled, the cover plate 11 with its downwardly extending flange 12 is rimmed or turned downwardly over the edge

4 of the shell, thus completing the button head and holding all of the parts in their assembled position.

In the bottom of the hub of the shell 2 5 there is a very small opening or prick-punch 13 through which the prong 14 of the tack 15 is to be passed.

When the button is to be applied to the goods, the prong 14 of the tack will be mechanically forced through the strip of goods 10 16 and up through the prick-punch into the hub 2 of the shell, and the prong of the tack being much greater in diameter than the diameter of the prick-punch, will force some 15 of the edges 17 of the stock about the prick-punch up into the restricted or constricted opening 9 of the anvil 5 as will be readily understood from Fig. 2.

The prong 14 will be jammed up into the 20 steel slug or rather into the recess or chamber 8 in the shank of the slug and will be so bent or multilated as at 18 that it will fill up the rounded chamber and of course by also having the constricted opening 9 it will 25 be impossible to ever pull the tack away from the button head.

The edges 17 of the stock also being forced 30 into the edge of the constricted opening 9 will help support the sides of the tack in the opening and help to keep the tack in line and add rigidity to the tack with relation to the button head.

It will be noticed that the shank of the hub is nearly as great in cross section or 35 diameter as the diameter of the hub of the shell so that together with the small plate 10 the shell is practically filled up when the cover is applied.

It will also be perfectly obvious without 40 being shown in the drawings, that the little plate 10 might be dispensed with if desired and the plate 6 of the anvil 5 made thicker to compensate for the omission of this plate 10.

If the little plate 10 is to be omitted from 45 the shell, the thickness of the plate 6 of the anvil 5 will be dependent upon the height of the rim 4 of the button, as the cover should rest against the upper surface of the plate 6 when the button head is assembled.

This construction may be cheaper than if 50 an extra plate 10 is used and comes clearly within the province of my invention.

From the foregoing it will be seen that I

have produced an extremely simple tack button, the same consisting of but several parts and at the same time it is so constructed that the tack will, after once being multilated within the slug or anvil, never become detached therefrom.

Furthermore, each of the parts may be quickly stamped out; quickly assembled, and readily applied to the goods in an appropriate fastening machine.

Many slight changes might be made without in any way departing from the spirit and scope of the invention.

Having thus described the same, what I claim as new and desire to secure by Letters Patent is:

1. A tack button comprising a shell and a hub on said shell, said hub having a small perforation in the bottom, an anvil having a depending shank, said shank having a recess therein and the throat of the recess being constricted and in alignment with the small perforation in the bottom of the hub of the shell, the said anvil having its top portion in the form of a plate and extending to the outer periphery of the shell and a cover over the shell for locking the several parts in position.

2. A tack button comprising a shell having a hub, an anvil comprising an integral top plate and depending shank and said shank having a recess therein and the throat of the recess being constricted, the said shank of the anvil filling the hub of the shell, the recess of the shank adapted to receive a fastening member, the upper portion of the anvil having a plate extending outwardly to the periphery of the shell, a second plate lying on the said integral plate and a cover tightly locking the shell and anvil together.

3. A tack button comprising a shell having a hub and the hub having a prick-punch therein, an anvil comprising a top plate and a depending shank provided with a chamber having a constricted throat in alignment with the prick-punch of the shell, a second plate within the shell and lying on the top of the plate of the anvil, a cover about said shell, the chamber adapted to receive a portion of the metal of the hub and a tack fastener when the latter is jammed into the chamber of the anvil.

In testimony whereof I affix my signature.
WALTER T. ABEL.
